(57) **CLAIM**

The ornamental design for a portion of a multi-handled bag, as shown and described.

DESCRIPTION

FIG. 1 is a perspective view of a multi-handled bag showing our new design, the undisclosed rear is not part of the claimed design;

FIG. 2 is a top plan view thereof;

FIG. 3 is a front perspective view of a second embodiment thereof; the undisclosed rear is not part of the claimed design; and,

FIG. 4 is a front perspective view of a third embodiment thereof; the undisclosed rear is not part of the claimed design.

The uneven broken lines in the center portion of each bag shown in FIGS. 1-4 represent an unclaimed boundary of the design. The even broken lines within the end portions of FIGS. 1-3 indicate a perforation appearance, and the solid curved lines within the end portions of FIG. 4 indicates a cut-line appearance.
